UNITED STATES PATENT OFFICE.

RUDOLPH F. SCHILLER, OF SUN PRAIRIE, WISCONSIN.

SHOE-STRING TIP.

1,421,999.

Specification of Letters Patent. Patented July 4, 1922.

Application filed February 21, 1922. Serial No. 538,180.

To all whom it may concern:

Be it known that I, RUDOLPH F. SCHILLER, a citizen of the United States, residing at Sun Prairie, in the county of Dane and 5 State of Wisconsin, have invented new and useful Improvements in Shoe-String Tips, of which the following is a specification.

My present invention has reference to a novel and effective tip for shoe strings.

10 My object is to produce a tip for shoe strings that shall comprise a cylinder of woven wire or the like, and which is formed or otherwise provided with impinging elements to enter the shoe string when the shoe 15 string is inserted through the tip, the construction of the said tubular member rendering the same susceptible to longitudinal expansion and lateral contraction which is brought about by a longitudinal pulling on 20 the strands, so that the tip can be attached to the string in an easy, quick and thoroughly efficient manner.

The foregoing objects may be accomplished by a construction, combination and 25 arrangement of parts, such as is disclosed by the drawing which accompanies and which forms part of this specification.

In the drawing:—

Figure 1 is a side elevation of the tip, on 30 a greatly enlarged scale.

Figure 2 is a similar view showing the tip stretched from the end of a shoe string.

Figure 3 is an approximately central longitudinal sectional view of the construction 35 illustrated in Figure 2.

As disclosed by the drawing, the tip 1 for the shoe string 2 is of a tubular or cylindrical formation, the same being constructed of wire, tin, copper, or any other desired 40 metal or material. By reference to the drawing, it will be seen that the strands constituting the improvement are woven to

provide blocks which are arranged in diagonal series, the said blocks being diamond-shaped in plan, and any desired number of 45 these blocks are integrally formed with impinging elements 3 which enter the fabric string 2 when the cylindrical tip 1 is moved longitudinally on the string to expand the same and such longitudinal expansion 50 will cause the lateral contraction of the tip so that the impinging elements 3 will enter the shoe string. The impinging elements 3 are directed outwardly with respect to the ends of the shoe string and when the tip is 55 once positioned thereon the same cannot be pulled off of the string as is common with the ordinary classes of such tips.

Having described the invention, I claim:—

1. A tip for shoe strings comprising a cylindrical member having its bore provided with impinging elements, said tip designed, when inserted over a shoe string to be pulled from the opposite ends thereof to expand 65 the same longitudinally and to contract the same laterally and in such contraction to cause the impinging elements to enter the shoe string.

2. A tip for shoe strings comprising a 70 cylindrical member formed of woven material to provide diagonally arranged over and underlying portions, said tip having outwardly directed impinging elements in the bore thereof and being susceptible to 75 longitudinal expansion and to lateral contraction and when so expanded and contracted designed to have its impinging elements enter the shoe string when the latter is inserted through the tip.

In testimony whereof I affix my signature.

RUDOLPH F. SCHILLER.
